UNITED STATES PATENT OFFICE.

DAVILLA L. KLAHR, OF SHELBYVILLE, ILLINOIS.

TRICYCLE.

SPECIFICATION forming part of Letters Patent No. 447,331, dated March 3, 1891.

Application filed September 16, 1890. Serial No. 365,188. (No model.)

To all whom it may concern:

Be it known that I, DAVILLA L. KLAHR, a citizen of the United States, residing at Shelbyville, in the county of Shelby and State of Illinois, have invented a new and useful Tricycle, of which the following is a specification.

This invention relates to carriages and wagons, and more especially to that class thereof known as "velocipedes;" and the object of the same is to produce a tricycle driven by a coiled spring or springs carried on the body of the machine and adapted to be wound from time to time by the rider.

The invention consists of the details of construction and arrangement of parts necessary for effecting the desired end, together with certain auxiliaries tending to enhance the value of the whole, all as hereinafter more fully described and as illustrated in the drawings, in which—

Figure 1 is an elevation of this machine taken from the right side. Fig. 2 is a plan view. Fig. 3 is a bottom plan. Fig. 4 is a detail in perspective of the brake-operating and tension devices. Fig. 5 is a similar view of the steering mechanism. Fig. 6 is a longitudinal section.

Referring to the said drawings, the letter F designates a suitable frame-work composed of transverse front and rear bars connected by a number of longitudinal bars and supported by girders G, extending the length of the machine, as best seen in Fig. 3. Journaled in boxes X beneath the rear end of the frame-work is an axle A, having spring-clutches C on each end engaging the driving-wheels W, whereby the latter will be turned forwardly with the axle, but will be permitted to turn to the rear or to stand still independent of the motion of the axle, as is common in machines of this character. An upright shaft U is journaled in a suitable box at the forward end of the frame-work, and to the lower end of this shaft is attached the fork f, carrying the front or steering wheel w. Diagonal braces D extend rearwardly from this fork and carry a friction-wheel d at their upper end, which travels beneath a curved track T on the bottom of the frame-work F. The pivot of the friction-wheel d is extended into a hook H, and a chain N connects this hook with the lower end of the shaft, by which

means the fork and brace are prevented from spreading.

g is a segmental gear keyed to the upper end of the shaft U, and R is a rack-bar moving in suitable guides r and engaging said gear. Pivoted as at p to the rack-bar is a connecting or pitman rod P, whose other end is pivoted to the steering-lever 4. The latter is pivoted at the center of the disk Q, provided with a number of notches q in its edge, and a latch-lever 5, pivoted to the lever 4, operates a bolt Q', which engages said notches and holds the steering-lever 4 at any desired point.

The axle A is driven from one or more powerful coiled springs arranged within a drum M, mounted loosely upon a shaft a, which is supported above the axle in suitable boxes or journals x. From a sprocket-wheel W' on this drum a chain C' leads around a larger sprocket-wheel W² on another shaft a', whereby a decreased speed of rotation is given the second sprocket-wheel. On said shaft a' is another sprocket-wheel W³, from which leads a second chain C² forwardly to a smaller sprocket-wheel W⁴, located on another shaft a'', by which means an increase of speed is effected. On said shaft a'' is another sprocket-wheel W⁵ of considerable size, from which a chain C³ leads rearwardly to a smaller sprocket-wheel W⁶ upon the axle A, by which an increased speed of revolution is imparted thereto. By this means the rotation of the drum by the uncoiling of the spring drives the shaft a' rather slowly, which motion is communicated to the shaft a'' with an increased speed, and from this shaft to the axle also with an increased speed, whereby the motion of the drum is transmitted to the axle in a multiplied form. Upon the power-shaft a is a ratchet-wheel R', and a pawl P' engages this ratchet-wheel to prevent a retrograde movement of the same, due to the uncoiling of the spring. The latter is connected at its inner end to this shaft and at its outer end to the drum in a manner well understood in spring-motors. The spring is wound in the following manner, described below:

Upon the power-shaft a is a gear g', meshing with a gear g² on an idle-shaft i, journaled in one of the boxes x, and on this idle-shaft is a second gear g³, engaging a large gear

⁴, mounted on what I shall call the "winding-shaft" ⁵. Along each side of this large gear is a ratchet-wheel E, and below the frame-work is arranged a pair of loop-levers e, whose loops are drawn into the teeth of the ratchet-wheel E by coiled springs e'. The other ends of these loop-levers are pivotally connected to a long lever E' on either side of its pivotal support E² in the frame. To the other end ¹⁰ of the long lever E' is connected a pitman Y, which in turn is connected with the lower end of the winding-lever 1, which is journaled in the frame-work and rises upwardly along the right-hand side of the operator's seat. The long lever E' is preferably guided in a slotted plate L', depending from the frame-work. In order to wind the spring the winding-lever 1 is reciprocated, whereby the long lever E' is oscillated about its pivot E². This causes the ¹⁵ loop-levers e to alternately engage the ratchet-wheels E, and the winding-shaft ² is thereby intermittently turned. This motion is communicated through the gears g³, g², and g' to the main shaft a, whereby the inner end of ²⁰ the large coiled spring is wound, the unwinding of the outer end thereof being meanwhile uninterrupted. The ratchet-wheel R' and pawl P' prevents the return movement of the power-shaft, as above stated, and hence by a ²⁵ reciprocation of the winding-lever 1 power is stored, which may be afterward expended in driving the machine.

Journalized beneath the frame-work and across the same in front of the main wheels ³⁰ W is a shaft S', having brake-shoes S² on its ends, and keyed to this shaft is the brake-lever 2, which extends upwardly through the platform or floor Z of the device to within easy reach of the rider. The front edge of this ³⁵ lever is preferably provided with teeth j, adapted to be engaged by a pawl J, when desired, and when the lever is drawn to the rear the brakes are applied to the wheels, the pawl holding them in operative position. As soon as the pawl is disengaged from the teeth the ⁴⁰ coiled spring J' throws it out of the way, as shown in Fig. 1. By this means the speed of the tricycle may be retarded or checked entirely at the will of the rider.

⁴⁵ Upon a rearward extension F' of the frame-work is mounted a casting V, supporting a speed-governor of any desired construction, but preferably as described below. In a horizontal arm of this casting is journaled a short shaft having a band-pulley v on one end connected by a belt v' with another band-pulley v² on the axle, whereby motion of the latter is imparted to the band-pulley v. On said horizontal shaft is a bevel-gear intermeshing ⁵⁰ with another on the upright rotating portion V' of the governor. This portion carries the two weighted balls adapted to be thrown outwardly by centrifugal force, as well understood in speed-governors, and whose inner ends engage a grooved ring V², mounted on a vertically-moving rod V³. This rod slides ⁵⁵ freely through the upright portion V' and

the casting V, and its lower end rests upon the rear end of an arm S³, which is keyed at its front end on the shaft S'. Through this ⁷⁰ mechanism, should the device run away, as down a steep hill, the governor will move the rod V³ downwardly, depress the rear end of the arm S³, turn the shaft S', and automatically apply the brake-shoe S² to the wheel. ⁷⁵

The governor-arm S³ has a slot s' in its body, which moves over a vertical pin s², as best seen in Fig. 4, and depresses a coiled spring s³. The lower end of this coiled spring rests upon a lever t, which rests upon a cross-bar ⁸⁰ t' and whose front end is connected by a pitman t³ with the tension-lever 3. This lever is pivoted at one end in a standard t⁴, rising from the frame through the platform Z, and at its other end is adapted to engage beneath ⁸⁵ one of a number of teeth t⁵ upon a bar or plate also rising from the frame and extending through the platform Z. By this means the tension-lever 3 can be depressed to increase the resisting force of the coiled spring ⁹⁰ s³, which force tends to sustain the arm S³ and overcome the operative movement of the governor. Hence, when the rider desires to travel very swiftly he depresses the tension-lever 3 and locks it in depressed position, and ⁹⁵ the governor is thereby prevented from automatically applying the brakes until the increased resisting force of the spring s³ has been overcome by the centrifugal force of the governor, and this latter force can only be ¹⁰⁰ increased by the very rapid movement of the machine.

What is claimed as new is—

1. In a velocipede, the combination, with the frame-work F, having the curved track ¹⁰⁵ T, of the upright shaft U, journaled in said frame-work, the fork f, depending from said shaft, the steering-wheel w, journaled in said fork, the diagonal braces D, extending rearwardly from said fork, the friction-wheel d at the upper end of said braces moving beneath said track, the pivot of said wheel being extended into a hook H, and a chain N, connecting said hook with the lower end of said shaft, as and for the purpose set forth. ¹¹⁵

2. In a velocipede, the combination, with the upright shaft U, carrying the steering-wheel w and journaled in the frame-work F, and a segmental gear g, connected to the upper end of said shaft, of a rack-bar R, engaging said gear and moving in guides r, a connecting-rod p, pivoted to said rack-bar, a steering-lever 4, to which said connecting-rod is attached, a disk Q alongside said steering-lever and having a number of notches q in ¹²⁰ its edge, and a catch-lever 5, operating a bolt Q' and engaging said notches, as and for the purpose set forth.

3. In a tricycle, the combination, with the axle A, carrying the driving-wheels W, the ¹²⁵ driving-shaft a, the drum M, mounted loosely thereon and connected by sprockets and chains with said axle, and the spring S, connected at one end to said drum and at the

other end to said driving-shaft, of the winding-shaft i^2 , a large gear g^4 thereon, connected with a gear g' on the driving-shaft, a ratchet-wheel E on each side of said large gear, loop-levers e , engaging said ratchet-wheel, a long lever E' , pivoted to the frame, and to which said loop-levers are pivotally connected at either side of this pivot, and means for reciprocating said long lever, all as and for the purpose set forth.

4. The combination, with a spring-actuated driving-shaft a , a ratchet-wheel R' , and pawl P' , of a gear g' upon said driving-shaft, a winding-shaft i^2 , carrying a large gear g^4 , an interposed idle-shaft i , having gears g^2 and g^3 connecting said power and winding shafts, a ratchet-wheel E on each side of said large gear, loop-levers e , drawn into engagement with said ratchet-wheels by coiled springs e' , a long lever E' , pivoted at E^2 , the loop-levers being pivotally connected to said long lever on either side of its pivotal support, a slotted plate L' , in which the longer arm of said long lever is guided, a winding-lever l , and a pitman Y , connecting the winding-lever with the long lever, all as and for the purpose set forth.

5. In a tricycle, the combination, with the axle having driving-wheels and the driving mechanism connected with said axle, of a speed-governor carried upon the frame-work of the tricycle and connected by belt and pulleys to the axle, a shaft S' , journaled in said frame-work and having brake-shoes S^2 opposite said driving-wheels, and an arm S^3 , keyed 35 on said shaft and adapted to be actuated by

said governor to apply the brakes, as and under the circumstances set forth.

6. The combination, with a speed-governor, an arm S^3 , having a slot s' , which arm is operated by said speed-governor, a stationary pin s^2 , passing loosely through said slot, and a coiled spring s^3 , surrounding said pin below said arm, of a lever t , resting between its ends upon a stationary bar t' , one end of said lever supporting said coiled spring, and a handle-lever for operating the other end of said lever, the whole operating as and for the purpose set forth.

7. In a tricycle, the combination, with the main axle having driving-wheels and the driving mechanism connected with said axle, of a speed-governor carried upon the frame-work of the tricycle and driven by said axle, a brake-shaft S' , journaled in the frame-work and having shoes S^2 opposite said driving-wheel, a brake-handle lever on said shaft, an arm S^3 , keyed on said shaft and adapted to be actuated by said governor to apply the brakes, and a tension device, substantially as described, for imparting a regulated degree 55 of resistance to the movement of said arm, as and for the purpose hereinbefore set forth.

In testimony that I claim the foregoing as my own I have hereto affixed my signature in presence of two witnesses.
